(57) **CLAIM**

The ornamental design for a leafy ball finial, as shown and described.

DESCRIPTION

FIG. 1 shows a perspective view of a leafy ball finial incorporating the design;

FIG. 2 shows a front elevational view of the leafy ball finial shown in FIG. 1;

FIG. 3 shows a top plan view of the leafy ball finial shown in FIG. 1; and,

FIG. 4 shows a bottom plan view of the leafy ball finial shown in FIG. 1.

The broken line showing of a screw is for illustrative purposes only and forms no part of the claimed design.
